CONTROL DEVICE FOR PRINTING MACHINES

William Lewis, Cleveland, Ohio, assignor to R. Hoe & Co., Inc., New York, N. Y., a corporation of New York

Application January 15, 1938, Serial No. 185,168

3 Claims. (Cl. 101—378)

This invention relates to printing machines of the rotary cylinder type and more particularly to an improvement thereof by the provision of a safety device therefor, arranged in respect to the plate cylinder of the printing machine, whereby it may be operated with increased efficiency and safety.

The invention is particularly applicable to printing machines wherein plates are removably mounted on the plate cylinders, being clamped thereon by suitable plate clamping mechanism which is actuated by a removable wrench, or operating handle, and preferably one wherein such a wrench or operating handle is inserted and removed from the mechanism substantially radially with respect to the cylinder. A form of plate clamping mechanism with which the features and principles of this invention is especially applicable is shown and fully described in Patent Number 2,066,192 granted December 29, 1936.

One of the objects of this invention is to provide a safety device for a printing machine which is adapted to be associated with the plate cylinder and the plate clamping mechanism therefor, whereby the wrench, or operating handle, by which the plate clamping mechanism is actuated, is prevented from being placed in operating position without causing the machine to be inoperative.

Another object is to provide a safety device of the above nature, whereby the machine is prevented from being operated while the wrench, or operating handle, is in mechanism actuating position.

A further object is to provide for a printing machine of the above type, a safety device, including a machine control whereby the machine will be stopped and maintained inoperative whenever a wrench, or other operating means, for a plate clamping mechanism is disposed in an actuating position.

It is also an object of this invention to provide a safety device for a printing machine, of generally improved construction, whereby the same will be simple, durable and inexpensive in construction, as well as convenient, practical, serviceable and efficient in its use.

With the foregoing and other objects in view, which will appear as the description proceeds, the invention resides in the combination and arrangement of parts, and in the details of construction hereinafter described and claimed.

An embodiment of the invention is illustrated in the accompanying drawing, wherein:

Figure 1 is a diagrammatic side view of a por-

tion of a printing machine with a frame of the machine broken away to expose the ends of two pairs of plate and impression cylinders and the safety device of this invention associated therewith;

Figure 2 is a face view of one end of one of the plate cylinders looking in the direction of arrow 2 in Figure 1; and

Figure 3 is a sectional view taken on line 3—3 of Figure 2, the relative position of the plate cylinder being shown in dotted lines.

The portion of a printing machine illustrated in Figure 1 including two pairs of cooperating cylinders, each pair consisting of a plate cylinder 11 and an impression cylinder 12. Suitable ink supplying rollers 13 are provided and arranged in operable association with each plate cylinder 11. A web 14 is threaded between the cylinders of each pair and runs from a guide roller 15 to the first pair, then to the second pair, and from there to the remaining portion of the machine (not shown). The cylinders 11 and 12 and the roller 15 are journaled in and extend between machine frames 16 and 17.

As fully described in the above referred to patent, each plate cylinder 11 has a plurality of plates 18 clamped thereon by axially movable clamping members 19. The members 19 are moved into plate clamping position by a rockable member (not shown) which is adapted to be actuated by a swingable member 20, pivoted at 21, and operably connected to the rockable clamp actuating member. The member 20 is provided with a socket 22 into which a wrench, or operating handle 23 is adapted to be inserted to manually swing the same. In the form shown, the wrench 23 is insertable into the socket 22 substantially radially with respect to the cylinder 11. The outer wall of each socket 22 is formed by an arcuate plate 22a secured to the end of the cylinder by bolts or other suitable securing devices 22b.

As is shown by an elementary diagram in Figure 1, an electric motor 24 is provided for driving the printing machine. The motor 24 is connected to a line wire L2 by a conductor 25 and to one contact 26 of a switch 27 by a conductor 28. The other contact 29 of the switch 27 is connected by a conductor 31 to the line wire L1. The switch 27 is under the control of a solenoid 32 which is connected by a conductor 33 to the line wire L1 and by a conductor 34 to a normally open "start" push button 30. The push button 30 is connected to the line wire L2 through a normally closed "stop" push button 51 and a normally closed switch 35 of any suitable commercial type, and

which is shown mounted upon the machine frame 16 adjacent the end of the plate cylinder 11. The switch 35 is connected by a conductor 36 to the push button 51 and by a conductor 37 to the line 5 wire L2. Closing of the "start" push button 30 energizes the solenoid 32 which also actuates a switch 52 to close a maintaining circuit through the "stop" push button 51 and the switch 35. The normally closed switch 35 is provided with the 10 usual spring biased actuating lever 38, having a roller 39 mounted upon its free end, whereby the lever 38 may be actuated against its spring bias (not shown) to open the switch 35. Opening of the switch 35 deenergizes the solenoid 32 by opening 15 the circuit through the "stop" push button 51 and switch 52 whereby the switch 27 opens and the motor 24 stops, or is prevented from being operated by the "start" push button 30.

The removable wrench, or operating handle 23 20 during its clamp actuating movements and while in the socket 22, may assume any one of a plurality of the positions indicated by dotted lines in Figure 3, and provision is herein shown of a safety device whereby, when the wrench 23 is 25 inserted in the socket 22, the switch 35 is opened and the motor 24 is prevented from being operated. Such a provision eliminates all possibility of the machine operator being injured or damage being caused to the adjacent machine parts 30 and mechanisms, should the machine be started before the wrench is removed. The device illustrated embodies the features and principles of this invention in its simplest form and includes a bar 41 which is hinged at one end to a strap 35 bracket 42, upon a hinge pin 43. The bracket 42 is secured to the adjacent machine frame 16 by bolts 44. The bar 41 extends across the axis of the cylinder 11 at one side thereof and overlies the socket 22. The bar 41 has an intermediate 40 portion 45 of sufficient length to block the insertion of the wrench 23 into the socket 22 at any one of its possible plurality of operating positions, as indicated by dotted lines in Figure 3.

The bar 41 is, in this instance, hinged to swing 45 axially of the cylinder 11, and the portion 45 may be maintained in socket overlying position as shown in full lines in Figure 2 by the biasing spring for the lever 38 of the switch 35, or by a spring 46 arranged to react between the free end 47 of the bar 41 and the adjacent machine frame 16, as shown in Figure 2. A movement limiting screw 48 is provided to prevent the bar 41 from swinging against the end of the cylinder 11 and to insure its proper position relatively 50 to the socket 22. Attempted insertion of the wrench 23, or similar tool, into the socket 22 will move, or, as in this instance, swing the bar portion 45 about the hinge pin 43 toward the machine frame 16 and axially with respect to the 55 cylinder 11. During such movement of the bar portion 45, the switch operating lever 38 will be swung by the engagement of the roller 39 with the bar portion 45, the roller 39 being disposed in the path of movement of the bar portion 45 for this purpose by mounting the switch 35 to the 60 machine frame 16 by a bracket 49.

The device of this invention operates to cover 65 whichever of the sockets 22 is disposed in wrench receiving position, to prevent insertion of the 70 wrench without insuring that the machine is made inoperative. This is accomplished by the opening of the machine control switch 35 whenever the wrench is inserted into the socket 22, and by this switch being maintained in open circuit condition as long as the wrench 23 remains 75

in the socket 22. The arrangement is particularly convenient to use, as the bar portion 45 overlying the socket 22 is readily moved into switch actuating position by the wrench 23 when it is inserted into the socket 22. When desiring to slightly rotate the cylinder 11 during the placing of plates 18 thereon, the switch 35 may be actuated by manually manipulating the bar 41 to swing the lever 38.

It will be understood that the invention may 10 be embodied in other specific forms without departing from the spirit or essential attributes thereof, and it is therefore desired that the present embodiment be considered in all respects as 15 illustrative and not restrictive, and it will be further understood that each and every novel 20 feature and combination present in or possessed by the mechanism herein disclosed forms a part of the invention included in this application.

What I claim is:

1. In a printing machine, a frame, a plate cylinder journaled in said frame and having plate-clamping mechanism mounted thereon including axially-slidable plate clamps, an electric motor for rotating said plate cylinder, a control switch for said motor, the plate-clamping mechanism having a tool-receiving socket pivotally supported relative to the cylinder on an axially-extending pivot and operable to operate the plate clamps, the socket extending radially from its 30 pivotal support and swingably operable in a plane perpendicular to the cylinder axis, a straight bar pivotally secured at one terminal relative to the frame and extending perpendicularly across the cylinder so that when in normal position a portion of the bar radially covers the tool-receiving socket, yieldable means engaging the opposed 35 terminal of the bar for maintaining the bar in normal socket-covering position, the socket securing an operating tool which is radially insertable 40 therein when the said bar is axially moved from its normal socket-covering position, the radial positioning of the tool into the tool-receiving 45 socket being prevented by the interposition of the said bar when in its normal position, the control switch being operably connected with the said bar and movable to circuit breaking position by the movement of the bar from its normal 50 socket-covering position thereby breaking the electric circuit to the electric motor to prevent the operation of the motor while the bar is biased away from its normal position by the presence of the radially-disposed operating tool in the tool-receiving socket.

2. In a printing machine, a frame, a plate cylinder journaled in said frame and having plate-clamping mechanism thereon including axially-slidable plate clamps, an electric motor for rotating said plate cylinder, a control switch for said motor, the plate-clamping mechanism 60 having a tool-receiving socket pivotally supported relative to the cylinder on an axially-extending pivot and operable to operate the plate clamps, the socket extending radially from its pivotal support and swingably operable 65 in a plane perpendicular to the cylinder axis, a straight bar pivotally secured at one terminal relative to the frame and extending perpendicularly across the cylinder so that when in normal position a portion of the bar radially covers the 70 tool-receiving socket, adjustable yieldable means engaging the opposed terminal of the bar for maintaining the bar in predetermined normal socket-covering position, the socket receiving an operating tool which is radially insertable there- 75

- in when the said bar is moved from its normal socket-covering position, the radial positioning of the tool into the tool-receiving socket being prevented by the interposition of the said bar when in its normal position, the control switch being operably connected with the said bar and movable to circuit-breaking position by the movement of the bar from its normal socket-covering position thereby breaking the electric circuit to the electric motor to prevent the operation of the motor while the bar is biased away from its normal position by the presence of the radially-disposed operating tool in the tool-receiving socket.
15. 3. In a printing machine, a frame, a plate cylinder journaled in said frame and having plate-clamping mechanism mounted thereon including axially slideable plate clamps, an electric motor for rotating said plate cylinder, a control switch for said motor, the plate-clamping mechanism having a flat rectangular tool-receiving socket to rigidly support a tool, the socket being pivotally supported relative to the cylinder on an axially-extending pivot and operable to operate the plate clamps, the socket extending radially from its pivotal support and swingably operable in a plane perpendicular to the axis of the cylinder, a straight bar pivotally secured at one terminal relative to the frame and extending perpendicularly across the cylinder so that when in normal position a portion of the bar covers the tool-receiving terminal of the socket, yieldable means engaging the opposed terminal of the bar for maintaining the bar in normal socket-covering position, adjustable means controlling the amplitude of movement of the bar about its pivotal terminal, the said socket receiving a flat operating tool which is radially insertable therein when the said bar is axially moved from its normal socket-covering position, the tool being securely held in radial position by the socket, the radial positioning of the tool into the tool-receiving socket being prevented by the interposition of the said bar when in its normal position, the control switch being operably connected with the said bar and movable to circuit breaking position by the movement of the bar away from its normal socket-covering position thereby breaking the electric circuit to the electric motor to prevent the operation of the motor while the bar is biased away from its normal socket-covering position by the presence of the radially-disposed operating tool in the tool-receiving socket, the operating tool when held in the socket engaging the bar to prevent it returning to normal socket-covering position.

WILLIAM LEWIS.
